(57) **CLAIM**

The ornamental design for a container lid component, as shown and described.

DESCRIPTION

FIG. 1 is a front left perspective view of a container lid component according to the present invention.

FIG. 2 is a front view thereof; and,

FIG. 3 is a top view thereof.

The dash lines are shown to illustrate environmental aspects of the invention and these portions form no part of the claimed invention.

1 Claim, 3 Drawing Sheets

FIG. 1

FIG. 2

FIG. 3
